ADJUSTABLE COMBINATION KEYLESS LOCK

Joseph L. Justinian, New Orleans, La.

Application March 5, 1947, Serial No. 732,587

3 Claims. (Cl. 70—312)

1

The present invention relates to new and useful improvements in locks generally and more particularly to a keyless lock, commonly known as permutation or combination lock.

An important object of the present invention is to provide a lock of this character including a plurality of rotatable permutation disks through which a locking bolt is axially slidable together with means for locking the bolt in its projected position by a rotary movement of one or more of said disks, the bolt being retractible upon a return of the disks to their originally set position.

A further object of the invention is to provide a lock of this character including rotatable permutation disks having the number combinations on the periphery thereof corresponding with internal radial slots into which locking pins carried by the bolt are received, the bolt being movable into its projected locking position by a setting of the numbers of the disks in any combination, whereby the combination may be changed each time the bolt is projected into its locking position, if desired.

Another object of the invention is to provide a keyless lock of this character of simple and practical construction, which is efficient and reliable in operation, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a top plan view;

Figure 2 is an end elevational view;

Figure 3 is a transverse sectional view taken on the line 3—3 of Figure 1;

Figure 4 is a longitudinal sectional view taken on the line 4—4 of Figure 1;

Figure 5 is a group perspective view showing a portion of the housing provided with the guide for one side of the locking pins removed;

Figure 6 is a sectional view taken on the line 6—6 of Figure 5, and

Figure 7 is an enlarged perspective view of the base.

Referring now to the drawings in detail, wherefore for the purpose of illustration I have disclosed a preferred embodiment of the invention, the numeral 5 designates the lock housing generally which includes a base 6 of substantially Y-shaped construction including a pair of spaced apart parallel base members 8 and an extension 7 projecting from the connected ends of the parallel members. The pair of spaced parallel members 8 have transverse grooves 9 in the upper surface thereof and in which the lower end edges

2

of flat upstanding separators 10 are received and including an inner separator 10a suitably secured at the inner end of the extension 7. The ends of the members 8 are closed by a plate 11 extending parallel to the separators and the ends of the separators and the ends of the plate 11 are enclosed in boxes 12 and 13 to secure the separators and plate 11 in assembled relation with respect to each other. The boxes 12 and 13 extend under the members 8 of the frame as shown more clearly in Figure 3 of the drawings and the top of the boxes overlie the upper edges of the separators and plate 11.

The separators 10 and 10a are formed with aligned openings 14 aligned with an opening 15 in the plate 11 for slidably receiving a bolt 16 which is movable into and out of projected position at the outer side of the plate 11.

A plurality of permutation disks 17 are positioned between the separators 10 for free rotation on the bolt 16, the disks having scalloped peripheries to provide ribs 18 and valleys 19 therebetween, the valleys having the combination numbers 20 marked or otherwise carried thereon. Each of the disks is formed with a plurality of internal radially extending slots 21 extending outwardly from the central opening 22 of the disks, the slots being aligned radially with the ribs 18 on the periphery thereof.

Each of the separators 10 are also formed with a slot 23 extending through its upper edge from the opening therein for aligning with one of the slots 21 of the disks.

An aligning bar 24 is supported in a horizontal elevated position above the slots 23 and transversely of the disks 17 to provide a sighting alignment for the ribs of the disks with the slots 23 whereby to assure a proper alignment of the slots 23 with one of the slots 21 of the disks. The aligning bar 24 is supported at one end by a block 25 on the upper edge of the plate 11.

The inner end of the bolt 16 is reduced as shown at 26 and mounted for free rotation thereon are a plurality of rings 27 each having a locking pin 28 extending radially therefrom. The inner end of the bolt 16 is secured in a slide 29 by means of a pin or the like 30 and the slide is slidably mounted in a channel 31 rising from the extension 7 of the base, the channel being formed by an upstanding wall 32 at one side of the extension and an upstanding wall 33 adjacent the other side of the extension and inwardly from the adjacent edge thereof as shown in Figure 5 of the drawings. The upper edge of the wall 32 is formed on its inner side with a guide channel 34 which overlies one side of the slide 29 and the guide channel 34 forms a guide at one side of the pins 28.

The slide 29 is enclosed in a cover 35 which telescopes over the side wall 32 as well as over

the opposite side of the extension 7 and end thereof. A rib 36 extends downwardly from the inside of the cover for engagement in the channel 34 and a second rib 37 also extends downwardly from the top of the cover in parallelism with the rib 36 to form a guide for the pins 28 at the opposite side thereof. The channel 34 and guide rib 37 thus maintain the pins 28 in an upstanding position for guiding the pins into the slots 23 of the separators 10 and into the slots 21 of the permutation disks 17.

The top of the cover 35 is also formed with a longitudinally extending slot 38 in which a handle 39 is slidably received, the handle extending upwardly from the slide 29 and is provided with a finger gripping knob 40 at its upper end.

In the operation of the device the bolt 16 is projected and retracted by the handle 39 and in order to project the bolt the permutation disks 17 are set to form a desired combination of the numbers 20 by aligning the ribs 18 of the selected numbers with the aligning bar 24 as shown in Figure 1 of the drawings.

The bolt 16 is then moved by the handle 39 into its projected position whereupon the locking pins 28 will pass through the slots 23 of the separators 10 and into the slots 21 of the respective permutation disks as shown in Figure 4 of the drawings. Any one or all of the permutation disks 17 may then be rotated which thereby rotates the rings 27 carrying the pins 28 to move the pins 28 out of alignment with the slots 23 and the bolt is thus locked against retracting movement.

By returning the disks 17 to their originally set position the pins 28 will then again be aligned with the slots 23 and the bolt may then be retracted.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

What I claim is:

1. A keyless lock comprising a housing, a bolt slidably mounted in the housing for projecting and retracting movement, a plurality of permutation disks rotatably carried by the bolt and having internal radial slots, separators between adjacent disks and at one end of the disks, each separator having a stationary slot aligned with each other and also aligned with one of the slots of the disks when the latter are held in a predetermined position, a plurality of rings rotatably mounted on the bolt and movable therewith axially of the disks, locking pins projecting radially from the rings for passing through the stationary slots and entering the radial slots of the respective disks upon a projecting movement of the bolt, any one of said pins being movable out of alignment with the stationary slots upon a predetermined rotation of its associated disk to lock the bolt against retracting movement, said pins being returned to an aligned position with the stationary slots upon a return of the disks to a set position,

manually operated means for projecting and retracting the bolt, and means providing a guide channel in the housing for the pins to maintain the pins in aligned position with the stationary slots when moved beyond the separators upon retracting movement of the bolt and to guide the pins in a position for reentering the slots upon a projecting movement of the bolt.

2. A keyless lock comprising a housing, a bolt 10 slidably mounted in the housing for projecting and retracting movement, a plurality of permutation disks rotatably carried by the bolt and having internal radial slots, means providing a stationary guide slot in the housing aligned with 15 one of the slots of the disks when the latter are held in a predetermined position, a plurality of rings 20 rotatably mounted on the bolt and movable therewith axially of the disks, locking pins projecting radially from the rings for passing through the stationary slot and entering the radial slots of the disks upon a projecting movement of the bolt, any one of said pins being movable out of alignment with the stationary slot upon a predetermined rotation of its associated disk to lock the bolt against retracting movement, said disks having aligning elements 25 on the periphery thereof for indicating the position of the respective radial slots, and an aligning bar carried by the housing and extending 30 transversely of the periphery of the disks, said bar being in alignment with the stationary slot.
3. A keyless lock comprising a housing, a bolt 35 slidably mounted in the housing for projecting and retracting movement, a plurality of permutation disks rotatably carried by the bolt and having internal radial slots, separators between adjacent disks and at one end of the disks, each separator having a stationary slot aligned with 40 each other and also aligned with one of the slots of the disks when the latter are held in a predetermined position, a plurality of rings rotatably mounted on the bolt and movable therewith axially of the disks, locking pins projecting radially from the rings for passing through the 45 stationary slots and entering the radial slots of the respective disks upon a projecting movement of the bolt, any one of said pins being movable out of alignment with the stationary slots upon a predetermined rotation of its associated disk to lock the bolt against retracting movement, said pins being returned to an aligned position with the stationary slots upon a 50 return of the disks to a set position, a slide secured to the rear end of the bolt, a guide 55 for the slide including a rectangular housing having a longitudinal slot, a handle carried by the slide working in the last-named slot, and means providing a guide channel in the housing for said pins to maintain the pins in aligned position with the stationary slots when moved beyond the separators upon retracting movement of the bolt and to guide the pins in a position for reentering the slots upon a projecting movement of the bolt.

JOSEPH L. JUSTINIAN.
